UNITED STATES PATENT OFFICE.

GUSTAV STRANDT, OF MILWAUKEE, WISCONSIN.

MILK-BOTTLING MACHINE.

1,011,264.

Specification of Letters Patent. Patented Dec. 12, 1911.

Application filed April 18, 1910. Serial No. 555,993.

To all whom it may concern:

Be it known that I, GUSTAV STRANDT, a citizen of the United States, residing at Milwaukee, county of Milwaukee, and State of Wisconsin, have invented new and useful Improvements in Milk-Bottling Machines, of which the following is a specification.

My invention relates to improvements in bottle filling machines, and it pertains more especially, among other things—1st, to the device for automatically conveying the bottles from a stationary platform to a revolute conveyer; 2nd, to the device for raising and filling the bottles while they are being moved forward by the revolute conveyer; 3rd, to the device for removing the bottles from the revolute conveyer to the capping device; and 4th, to the device for communicating motion from the driving mechanism of the machine to the capper, said several parts being so constructed and their movements so timed that each is adapted to coöperate with the others in automatically performing the several functions named, whereby a large amount of manual labor heretofore required in doing such work is dispensed with and the work is much more rapidly done at but slight expense for manual labor.

My invention is further explained by reference to the accompanying drawings, in which—

Figure 1 represents a side view. Fig. 2 is a top view. Fig. 3 is a bottom view. Fig. 4 is an end view, part in section. Fig. 5 is a detail of the device for adjusting the tank to bottles of different height. Fig. 6 is a side view and Fig. 7 is an end view of a portion of the conveyer. Fig. 8 is a detail in vertical section of one of the bottle supporting disks and the device for automatically raising and lowering the same as the bottles are being moved forward by the conveyer. Fig. 9 is a modified form of the device shown in Fig. 8. Fig. 10 is a detail of the conveyer showing the modified form of the device for communicating motion to the bottle supporting disks as the conveyer is being revolved. Fig. 11 is a bottom view of the conveyer. Fig. 12 is a detail of the device for moving the bottles from the conveyer to the capper, and Fig. 13 is a plan view of the device shown in Fig. 12.

Like parts are identified by the same ref-

erence numerals throughout the several views.

1 represents a stationary platform or table, upon which the bottles are manually placed preparatory to being moved forward by the table supported conveyer, which conveyer comprises an endless chain 2 and the laterally projecting arms 2'. The chain 2 is supported upon three sprocket wheels 3, 4 and 5, motion being communicated from a source of power to such conveyer through the driving pulley 6, shaft 7, miter gears 8 and 9, vertical shaft 10, pinions 11, 12 and 13, and vertical shaft 14, which vertical shaft 14 is affixed at its upper end to said sprocket wheel 3, whereby as the bottles are placed upon the platform 1, they are carried forward by the radial arms 2', as indicated in Fig. 2, to the annular series of disks 15 of the revolute conveyer. The revolute conveyer comprises the central member 23, revolute platforms 24 and 24' and the annular series of U-shaped arms 16. Motion is communicated from a moving power to the shaft 17, and from thence to said annular series of disks through the driving pulley 6, horizontal shaft 7, miter gears 18 and 19, vertical shaft 20, pinion 21, and gear wheel 22, which gear wheel 22 is mounted upon and communicates motion to said vertical shaft 17. Said annular series of disks 15 are supported from the side of the gear wheel 22 through the central member 23, annular revolute platform 24 and vertical members 25. The vertical platform is provided with a series of apertures 26 for the reception of the vertical members 25, which have a vertical movement upwardly and downwardly in said apertures as said platform 24 is revolved.

The lower ends of the vertical members 25 are provided with anti-friction bearings 27, which are adapted to rest upon the annular track 28, which track 28 is supported from the stationary frame 29 by a series of brackets 30. The annular track 28 is curved upwardly and downwardly, whereby as the roller bearings 27 traverse the same, the disks 15 and disk supporting members 25 will be caused to gradually rise and fall as they are being revolved by the revolute conveyer over said stationary track 28, and whereby the bottles which are supported on said disks, will be brought into contact with the filling nozzles 31. The filling nozzles 31

are respectively connected with the lower side of the liquid tank 32 and said tank 32 is supported upon and revolved with said shaft 17. The nozzles 31 are of ordinary construction and are adapted, as the bottles are pressed upwardly against them, to open a liquid controlling valve, whereby the bottles are simultaneously filled as they are revolved with said tank. When, however, the 10 bottles have been filled, the movement of the machine is so timed that they will pass from the upper plane 33 of the track to the lower plane 34, and in so doing said disks will be caused to descend a distance corresponding 15 with the different planes of said track, whereby the bottles will be brought out of contact with said nozzles, preparatory to being removed from their supporting disks.

When the bottles have been successively 20 filled and have completed their revolution with the revoluble platforms 24, the bottles will be brought into contact with the stationary angular arms 35, whereby they will be removed from the disks 15 of the annular 25 series to the stationary platform 1 in the space 36. When two of the bottles have been thus deposited in the space 36, they are adapted to be carried forward by the reciprocating arms 37, 37 and deposited 30 under the capper, preparatory to being capped. Motion is communicated from the shaft 7 to the reciprocating arms 37 through the miter gears 8 and 39, shaft 40, wheel 41, pitman 42, link 43, two armed lever 44, pivotal bolt 45, bracket 46, reciprocating guide bearing 47, bracket 48, vertical standards 49, 49, arm supporting members 50, 50 and arms 37, 37.

It will be understood that the platform 40 1 is provided with a longitudinal slot 52 for the reception of the bracket 48, and said bracket 48 is rigidly affixed to the reciprocating guide bearings 47, which guide bearings 47 are slidably supported from the 45 lower side of the platform 1 by the stationary guide bearings 53, as more clearly shown in Fig. 12 of the drawings. The arms 37 are rigidly affixed to the supporting members 50 and said supporting members 50 are 50 revolvably supported from the vertical standards 49 and are yieldingly retained in place by the spiral springs 54, one end of said springs being rigidly affixed to the bracket 48, while their opposite ends are rigidly af- 55 fixed to said arm supporting member 50, whereby said arms are normally retained at nearly right angles to the supporting bracket, but are adapted to be inclined at an angle to their supporting bracket, and 60 thrown toward the right, reference being had to Fig. 2, as they are brought in contact with the bottles. Thus it will be obvious that when two bottles are in place in the space 36 and the bracket 48 is moved 65 toward the left, as previously described, said

arms 37 will be inclined toward the right until they pass such bottles, when they will be thrown by the recoil of said springs back to their normal position at right angles to said bracket, preparatory to being moved 70 in the opposite direction by the action of the machine, whereby such bottles will be moved forward from the space 36 to and under the capper, preparatory to being capped. It will be understood that the co-operating 75 members of the machine are so timed that the bottles will be removed from the revoluble disks to the capping machine, as fast as they are filled, and that when two bottles have been thus filled, they will be displaced 80 and moved from the capping machine by contact of the next two succeeding bottles, as such bottles are moved forward by the action of said laterally projecting arms 37.

Referring to Fig. 1, the bottle A is sup- 85 ported upon the lower plane 34 of the annular track 28 and upon the same plane with the stationary platform or table 1. When, however, the bottles have moved forward toward the left, the supporting bearing 27 passes up the incline to the higher plane 33 of said track, whereby the bottles are brought in contact with the stoppers 31, through which they are filled from the tank 32, as previously described. The series of 90 bottles B, B, (Fig. 1), are indicated as sup- 95 ported on the higher plane of the track in contact with said stoppers. When, however, the machine is being used for filling bottles of different sizes from those shown, the space 100 between the tank 32 and the annular series of bottle supporting disks 15 must be increased or diminished to conform to the height of such bottles as are being thus filled. To accomplish this object, the shaft 17 is 105 slidably connected with the revoluble conveyer through which it passes, and a vertical movement is communicated to said shaft 17 from the manually operated lever 55 through the horizontal shaft 56, clutch members 57 and 58, gear wheel 60, the vertical series of gear teeth 61, and slidable collar 62. The slidable collar 62 is provided with a longitudinal aperture for the reception of the lower end of the shaft 17, which operates therein, and the shaft 17 has vertical bearings 63 which contact with the sides of the inclosing sleeve 64, whereby said sleeve 62 is prevented from revolving with the shaft 17. Thus it is obvious that by revolving the gear wheel 60 in contact with the vertical series of teeth 61 in one direction, said shaft 17 will be raised, while by revolving it in the opposite direction, said shaft will be lowered, whereby said tank 32, together with the nozzles 31 may be adjusted at the desired elevation above the bottle supporting disks to conform to bottles of va- 110 rious heights.

The clutch members 57 and 58 are locked 130

at the desired point of adjustment by the locking bar 65, which locking bar has 5 slideable bearings provided therefor in the clutch member 57 and it is adapted to engage any one of the several recesses 66 of the clutch member 58. The locking bar 65 is slidably supported at one end from the lever 55 in an aperture 67 provided therefor and is adapted to be moved forwardly and backwardly from its locked to its unlocked position by the angular arm 68, from which it is centrally supported. The angular arm 68 is pivotally supported from the arm 55 on the pin 69, and motion is communicated 10 from the hand of the operator to said angular arm, and from thence to the locking lever 65 through the link 70, pivotal bolt 71 and lever 72.

The contact bearings of the U-shaped arms 16 are preferably so formed as to fit 20 bottles of several different sizes. Fig. 2 of the drawings shows them formed for two different sizes of bottles. When the machine is being used for filling the larger sized bottles, they are adapted to contact with the two opposing bearings 73, 73, which form 25 arcs of the circle described by such larger bottles. When, however, the machine is used for filling smaller bottles, they are adapted to contact with the central bearing 74, which conforms to the arc of the circle described by the smaller bottles. It follows 30 that when the machine is being used for filling smaller bottles, it becomes necessary to move the annular series of arms 16 a partial revolution so as to bring the smaller 35 arc of the circle 74 directly above the bottle supporting disks, and to accomplish this object, all of said arms 16 are formed integrally with, or rigidly connected to the 40 annular collar 75, and the collar 75, together with said arms 16, are adapted to be automatically moved forwardly or backwardly as the tank 32 is raised or lowered. Motion 45 is communicated from said tank to said arms, through the pivotal bolt 76, bracket 77, links 78, arm 79, pivotal bolt 80, shaft 81, arm 82, and arm 83, which arm 83 has 50 loosely fitting bearings in the arm 82, whereby it will be obvious that as said tank 55 is raised for the reception of larger and higher bottles, said arms 16 will be moved forwardly or toward the left, reference being had to Fig. 2, whereby the larger arc 55 of the circle 73 will be brought above the bottle supporting disks 15. When, however, said tank 32 is lowered to conform to the height of smaller bottles, said bottle supporting arms 16 will be moved in the opposite 60 site direction, whereby the smaller arc of the circle 74 will be brought above the bottle supporting disks 15.

The shaft 17 is provided with a vertical key 84, which operates in the vertical recess 65 85 of the revolute platform 24', whereby as

said shaft 17 is revolved, motion will be communicated through said key to said platform, while said shaft 17 is free to be moved upwardly and downwardly through said platform without communicating motion thereto as may be required to adjust the tank to bottles of different sizes. The bottle supporting disks 15 are yieldingly supported from their antifriction bearings 27 through the slideable member 86, disk 87, and spiral spring 89, whereby the bottles supported on said disks 15 are yieldingly retained in contact with the nozzles 31, as they are being filled, and whereby the liability of becoming broken by contact with a stationary bearing, is avoided. While the bottle supporting disks 15 are shown as supported directly from the antifriction bearings 27 through the vertically moving member 86, in Figs. 1, 4 and 8, said disks are preferably supported from the anti-friction bearings 27 through the lever 90, pivotal shaft 91, bracket 92, lever 93, and contact bearing 94, which bearing 94 is adapted to contact with the disk 87 and thus communicate motion 95 to the bottle supporting disk 15, as shown in Figs. 9 and 10 of the drawings. By the arrangement shown in said Figs. 9 and 10, it will be understood that by making the lever 93 longer or shorter than the lever 90, the movements of the bottle supporting disks 15 may be increased or diminished without changing the relative position of the upper and lower planes of the track 28.

The so-called capper or device for placing 100 paper caps in the mouths of the bottles as they are being filled, forms the subject matter of another pending application and further description herein is therefore unnecessary. Said capper is however supported 105 from the stationary platform 1 by vertical standards 95, 95, and the same is connected with a movable member of the machine through the vertical rod 96, and motion is communicated to the vertical rod 96 from 110 the vertical shaft 10 of the machine through the miter gears 97 and 98, horizontal shaft 99, miter gears 100 and 101, shaft 102, crank 103, and pivotal bolt 104, whereby with each revolution of the crank 103, a vertical reciprocating movement is communicated to the vertical rod 96 and from thence to the operating mechanism of the capper, as previously described.

While the capper above described is 120 adapted to place the caps upon two bottles at a time, it will be obvious that cappers may be used which are adapted to place the caps in a greater or less number of bottles.

Having thus described my invention, what I claim as new, and desire to secure by Letters Patent, is—

1. In a device of the described class, the combination of a stationary platform, a bottle conveyer supported on said platform 130

and adapted to move the bottles therefrom to a revoluble conveyer, a revoluble conveyer, an annular series of bottle supporting disks carried by said conveyer, a liquid tank 5 revolubly supported above said revoluble conveyer, a plurality of nozzles suspended from said liquid tank, means for communicating motion from a motor driven shaft to said liquid tank and both of said conveyers, 10 means connected with said revoluble conveyer for successively raising and lowering the bottle supporting disks and bottles, whereby the mouths of said bottles, when raised, are brought into engagement with 15 the mouths of said nozzles and said bottles are filled as they are being revolved, bottle supporting arms, means connected with said tank for automatically adjusting the bottle supporting arms and means for removing 20 the bottles from the revoluble conveyer to said stationary platform after they have been filled and lowered.

2. In a device of the described class, the combination of a stationary platform, a 25 bottle conveyer supported on said platform and adapted to move the bottles therefrom to a revoluble conveyer, a revoluble conveyer, an annular series of bottle supporting disks carried by said conveyer, a liquid 30 tank revolubly supported above said revoluble conveyer, a plurality of nozzles suspended from said liquid tank, means for communicating motion from a motor driven shaft to said liquid tank and both of said 35 conveyers, means connected with said revoluble conveyer for successively raising and lowering the bottle supporting disks and bottles, whereby the mouths of said bottles, when raised, are brought into engagement 40 with the mouths of said nozzles and said bottles are filled as they are being revolved, means for removing the bottles from the revoluble conveyer to said stationary platform after they have been filled and lowered, 45 means for manually raising said tank to conform to the heights of bottles of different sizes, bottle supporting arms and means con-

nected with said tank for automatically adjusting the bottle supporting arms forwardly and backwardly as said tank is 50 raised and lowered, to conform to the diameter of bottles of different sizes.

3. In a device of the described class, the combination of a stationary platform, a bottle conveyer supported on said platform 55 and adapted to move the bottles therefrom to a revoluble conveyer, a revoluble conveyer, an annular series of bottle supporting disks carried by said conveyer, a liquid tank revolubly supported above said revoluble conveyer, a plurality of nozzles suspended from said liquid tank, means for communicating motion from a motor driven shaft to said liquid tank and both of said 60 conveyers, a stationary track formed on two different horizontal planes connected together by an intermediate inclined plane, a series of vertically moving members provided at their lower ends with roller bearings operating on said track and connected 65 at their upper ends with said bottle supporting disks for successively raising and lowering said bottle supporting disks and bottles, whereby the mouths of said bottles, when raised, are brought into engagement with the 70 mouths of said nozzles and said bottles are filled as they are being revolved, means for removing the bottles from the revoluble conveyer to said stationary platform after they have been filled and lowered, means for manually 75 raising said tank to conform to the heights of bottles of different sizes, bottle supporting arms and means connected with said tank for automatically adjusting the bottle supporting arms forwardly and backwardly as said tank is raised and lowered, to conform to the diameter of bottles of different 80 sizes.

In testimony whereof I affix my signature in the presence of two witnesses.

GUSTAV STRANDT.
